UNITED STATES PATENT OFFICE.

JULIUS C. RICHARDSON, OF PITTSBURG, PENNSYLVANIA, ASSIGNOR TO
PRISCILLA S. HUGUS, OF SAME PLACE.

MOLDING-MACHINE FOR HOLLOW WARE.

SPECIFICATION forming part of Letters Patent No. 425,255, dated April 8, 1890.

Application filed August 9, 1889. Serial No. 320,239. (No model.)

To all whom it may concern:

Be it known that I, JULIUS C. RICHARDSON, a citizen of the United States, residing at Pittsburg, in the county of Allegheny and 5 State of Pennsylvania, have invented certain new and useful Improvements in Molding-Machines for the Manufacture of Hollow Ware, of which the following is a specification.

The object of my invention is to manufacture hollow ware—such as skillets—in a simple and expeditious manner and at as small a cost as possible.

My invention consists in the approved apparatus hereinafter described, and designated 15 in the claims.

In the accompanying drawings, Figure 1 is a front elevation, partly in section, of a machine embodying my improvements. Fig. 2 is a perspective view, partly in section, of the 20 die-block and its top plate. Fig. 3 is a perspective view of the plate or blank from which the vessel is formed, and also the vessel struck up or dished to the desired shape; and Fig. 4 is a detail view showing a vertical section 25 through the devices for adjusting the plunger-rod.

In general outline the machine employed embodies suitable framing, a reciprocating plunger, a holder for the sheet or disk of metal 30 from which the vessel is formed, a die into which the sheet of metal is forced by the plunger, and an expeller for removing the dished vessel from its holder or die.

The machine shown in the drawings consists of a bed-frame A, on which is mounted an upright frame B, having a vertical central opening B', in which moves vertically the plunger-carrier C. A main driving-shaft D is journaled in the main frame B near its upper end and carries at one end a fly-wheel E and pulleys F. At the opposite end it is provided with a pinion G, which meshes with a cog-wheel H on the crank-shaft I, which is journaled in bearings in the frame above the 45 shaft D. The cog-wheel H is loose on the shaft I, but may be rigidly secured thereto by the clutch J, of any suitable construction, which is operated by a bell-crank lever J', connected to a vertical spring-actuated rod J'', 50 pivoted at its lower end to a treadle K, pref-

erably located under the bed-frame A. The plunger-carrier C is adapted to move up and down in the frame B, and is pivotally connected at its upper end to a screw-rod L. A screw-rod L' is connected at its upper end 55 with a crank M on the shaft I, and its lower screw-threaded end engages with a nut N, which nut also engages with the upper end of the screw-rod L. This nut may be adjusted to vary the length of the rods L and L' to adjust the distance between the plunger-carrier C and the nut M. The plunger O is removably secured to the plunger-carrier C, and its lower end is suitably shaped to correspond with the inside of the hollow-ware vessel or 60 dish which it is desired to form. By making the plunger removable different sizes of plungers may be used to form dishes or vessels of varying sizes.

The frame A is provided with a central 70 opening a, and the die-block P is provided with a central opening inclined to correspond with the shape of the vessel to be formed. The die-block is preferably provided with inclined or beveled sides, and is connected with 75 the frame by sliding it laterally into correspondingly beveled or inclined guides p. The top plate Q of the die-block is provided with a central opening Q', and is secured to the main die-block by bolts q and q'. Washers 80 q² are interposed between the upper face of the die-block and the top plate, and the nuts are secured to the bolts outside the top plate. By this arrangement a space is left between the die-block and top plate to receive the 85 sheet of metal or blank of which the vessel is to be formed. The bolts q are separated sufficiently to admit of the blank being slid into the opening q³ between the top plate and the die-block, and the bolts q' are so located that 90 the washers q² approximate the rear edge of the central openings in the top plate and the die-block and serve to center the plate R, from which the vessel S is formed. When the plate R is properly centered, the machine is 95 operated to force the plunger down upon the plate and bend it in the die to the desired form. The opening a in the bed-plate is somewhat larger in diameter than the opening at the bottom of the die, so that the plun- 100

ger will not abut against the framing. This opening should be larger than the bottom of the largest vessel made. When the vessel is formed, it is removed from the machine by the 5 expeller T, reciprocating vertically in the opening a and adapted to pass into the opening in the die and force the vessel out. The expeller is operated, preferably, by a treadle T'. Obviously the details of construction of the 10 machine may be somewhat varied.

So far as part of my invention is concerned any suitable apparatus may be employed for operating the plunger; but the apparatus shown and described is simple and efficient, 15 and is preferred.

By adjusting the nut N the depth of the vessel manufactured may be varied; and when there is a difference in the thickness of the metal—*i. e.*, if a blank thinner than usual is 20 used—the nut N may be adjusted to lengthen the rods L L', and by bringing the plunger down a second time the vessel may be completely formed.

It will be observed that the die-block is not 25 closed at the bottom, but is open, thus giving it a ring shape. Skillets of any desired depth may thus be formed by employing suitable plungers. The top plate, being held a suitable distance from the die-block, forms a 30 guide for the block and holds it properly for the action of the plunger.

I claim as my invention—

1. The combination, substantially as hereinbefore set forth, of the die-block, its top

plate, and devices interposed in the path of 35 the blank between the die-block and the top plate, which hold the plate a suitable distance above the die and constitute stops to limit the inward movement of the blank and to center it.

2. The combination, substantially as hereinbefore set forth, of the main frame, the reciprocating plunger, the die-block, its top plate, the bolts for securing the top plate to the die-block, two of which are arranged near 40 the outer edge of the die-block and two others near the inner edge of the opening in the die-block to center the blank, and washers on the bolts interposed between the top plate and the die-block.

3. The combination, substantially as hereinbefore set forth, of the main frame, a die-block having inclined or beveled sides engaging with correspondingly-beveled guides in the main frame, the plunger-carrier, the 45 plunger removably secured thereto, a crank-shaft, adjustable connections between the crank-shaft and the plunger-carrier, and the vertically-reciprocating expeller moving in an opening larger in diameter than the opening in the lower part of the die-block.

In testimony whereof I have hereunto subscribed my name.

JULIUS C. RICHARDSON.
